UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING MACHINES.

Application filed June 10, 1920. Serial No. 387,936.

To all whom it may concern:

Be it known that I, JAMES R. MOFFATT, a citizen of the United States, residing at Chicago, in the county of Cook, State of Illinois, have invented certain new and useful 5 Improvements in Feeding Mechanism for Sewing Machines, of which the following is a description, reference being had to the accompanying drawing, and to the figures 10 of reference marked thereon.

The invention relates to new and useful improvements in feeding mechanisms for sewing machines, and more particularly to a sewing machine having a standard carrying a work supporting arm in which the feeding mechanism is located.

An object of the invention is to provide a sewing machine of the above character with a feeding mechanism which is so constructed and arranged that the work supporting arm housing the feeding mechanism may be made relatively small throughout its entire length so that comparatively small tubular articles may be stitched on the machine.

A further object of the invention is to provide a machine of the above character having a differential feeding mechanism wherein the means for imparting longitudinal movements to the feed dogs is located in the standard of the machine, except for the longitudinally extending members which directly impart the movements to the feed members carrying the respective feed dogs.

These and other objects will in part be obvious and will in part be hereinafter more fully disclosed.

In the drawings which show by way of 40 illustration one embodiment of the invention:

Figure 1 is a side view of a portion of the machine having my improved means embodied therein;

Fig. 2 is a view from the rear of the machine with parts in section and parts broken away to show the mechanism for operating the feed dogs;

Fig. 3 is a view partly in plan and partly 50 in section showing a portion of the cylinder and showing the feeding mechanism, except for the eccentric straps, and eccentrics which operate the several parts of the feeding mechanism;

Fig. 4 is a view in longitudinal section

through a portion of the standard and the work supporting cylinder showing the feeding mechanism in side elevation;

Fig. 5 is a view showing more or less diagrammatically the mechanism for imparting longitudinal movements to the auxiliary feed dog, the feed dog being at the rear end of its stroke; and

Fig. 6 is a similar view but showing the feed dogs at the forward end of their stroke.

My improvement is directed to a machine of the general type shown and described in my prior Patent #1,209,609, granted December 19, 1916, wherein a work supporting cylinder is provided in which is located a feeding mechanism consisting of one main feed dog and an auxiliary feed dog disposed so as to feed the material lengthwise of the work supporting cylinder. It will be noted that the differential movements imparted to the main feed dog and auxiliary feed dog in said patent, are derived from devices located within the work supporting cylinder, and as a consequence, the cylinder is considerably enlarged adjacent the supporting standard to accommodate this mechanism. The present invention is directed to a rearrangement and modification of the parts shown in said patent so that the mechanism for imparting differential movements to the main feed dog and auxiliary feed dog may be placed in the standard and the work supporting cylinder therefor may be made very much smaller, thus providing a machine wherein very small tubular articles may be stitched.

Referring more in detail to the drawings, my improved machine consists of a supporting bed 1 carrying a standard 2 on which is mounted an overhanging arm 3. Projecting from said standard 2 is a work supporting cylinder 4. Said cylinder is bolted to the standard and suspended thereby and extends outwardly therefrom underneath the overhanging arm 3. Mounted to reciprocate in the overhanging arm 3 is a needle bar 5 carrying a needle 6. Also mounted on the overhanging arm is a presser foot 7 which operates to hold the material on the work support. As shown in the drawings, the material is fed lengthwise of the work support by a main feed dog 8 located in rear of the needle, and the auxiliary feed dog 9 located in front of the needle. As in my prior patent, it is desirable to give a

slightly different movement to the auxiliary feed dog, or what is known in the art, a differential feeding movement is imparted to the main and auxiliary feed dogs. Extending transversely of the standard 2 is a main shaft 10 and the needle bar is reciprocated by suitable connections with said cross shaft.

The main feed dog 8 is mounted on the main feed bar 11. This main feed bar 11 is formed with a cylindrical section 12 on which is mounted a sleeve 13. The auxiliary feed bar 9 is carried by this sleeve 13. The main feed bar 11 is formed with a fork 14 at its rear end, which straddles the pin 15 carried by the oscillating bracket 16. This oscillating bracket 16 is pivoted at 17 and is swung about this pivot by means of an eccentric strap 18 co-operating with the eccentric 19 on the cross shaft 10. Said eccentric strap 18 is pivoted at 20 to the oscillating bracket 16. A link 21 is pivoted at 22 to the feed bar 11 and the other end of this link is pivoted to an adjustable pivot bolt 23. Said pivot bolt 23 may be shifted longitudinally in a slot 24 in the bracket 16, and as this adjustable pivot bolt 23 is shifted, it is moved toward and from the pivot point 17 of the oscillating bracket 16. As this bracket oscillates, this link 21 imparts endwise movements to the feed bar 11 and the length of the movement imparted to the feed bar depends upon the position of the adjustable bolt 23. Said adjustable bolt 23 is extended as clearly shown in Fig. 3 so as to provide means whereby it may be easily shifted by hand.

The feed dogs are raised and lowered by raising and lowering the front end of the main feed bar which swings on the pivot pin 15, during these movements. Extending lengthwise of the work supporting cylinder 4 is a lever 25. This lever is pivoted at 26. The front end of said lever is also pivoted to a link 27 at 28 and the upper end of this link is pivoted at 29 to the sleeve 13 carrying the auxiliary feed dog. This sleeve, as above noted, is mounted on the cylindrical portion 12 of the main feed bar 11 and as the sleeve moves up and down, the forward end of the feed bar will move up and down. The section 11 of the feed bar is in the form of a sleeve which is split at its front end and the cylindrical section 12 extends into said sleeve section and is clamped therein by means of a screw 30. The rear end of the lever 25 is pivoted at 31 to an eccentric strap 32 which co-operates with an eccentric 33 on the shaft 10. As this shaft rotates, the lever 25 will be oscillated and this will simultaneously raise and lower the feed dogs. As a means for moving the sleeve endwise for imparting feeding movements to the auxiliary feed dog, I have provided a rock lever 34 which

is pivoted at 35 to the main feed bar so that said rock lever moves back and forth with the main feed bar. Said rock lever has a downwardly extending arm 36 provided with a slot 37. A link 38 is pivoted to a pivot bolt 39 adapted to slide in the slot 37. The other end of the link 38 is pivoted at 40 to the sleeve 13 carrying the auxiliary feed dog. Said link is extended to form a handle 41 by which it may be shifted to change the point of connection with the arm 36, that is, to move said point of connection toward and from the pivot point 35 of the rock lever 34. Mounted on the oscillating bracket 16 is a rigid arm 42 and said arm 42 is pivotally connected by link 43 with the arm 44 of the rock lever 34. As the bracket 16 oscillates, it raises and lowers the arm 42, and through this pivotal link connection 43 will swing the rock lever 34 on its pivot 35. It will be noted that the arm 42 partakes of the same general movement as the main feed bar, that is, as the main feed bar moves to the right, the arm 42 has a bodily movement to the right and as the main feed bar moves to the left, the arm 42 has a movement to the left. This bodily movement of the arm 42 in a measure, is similar to the bodily movements of the rock lever 34, but said arm 42 as it moves bodily, also swings up and down and this brings about a slight oscillation to the rock lever 34. Through this mechanism, the sleeve 13 is given a bodily movement back and forth in timing with the bodily movements of the feed bar back and forth, and an additional movement, the extent of which depends upon the position of the adjustable pivot bolt 39.

It is to be noted that the oscillating bracket 16, the eccentric strap and eccentric for oscillating the same, are all disposed within the standard. Also the pivot pin 15 for the feed bar is likewise in the standard, and the main feed bar extends into the standard. In fact, all the mechanism for moving the feed dogs back and forth is in the standard, except the rock lever and the link connections to the main feed bar, and the sleeve carrying the auxiliary feed dog. By this arrangement of parts, the work supporting cylinder at the point where it joins the standard, may be made relatively small so that small tubular articles may be stitched.

It is obvious that minor changes in the details of construction and arrangement of parts may be made without departing from the spirit of the invention as set forth in the appended claims.

Having thus described the invention, what I claim as new and desire to secure by Letters-Patent, is:

1. A sewing machine including in combination a standard, a relatively small work supporting cylinder carried thereby and projecting therefrom, a main feed bar lo-

- cated in said cylinder and extending lengthwise thereof into said standard, a main feed dog carried thereby, a sleeve mounted on said main feed bar for endwise movement thereon, an auxiliary feed dog carried by said sleeve, means for raising and lowering the front end of said feed bar together with the sleeve thereon, an oscillating member located in said standard, means for oscillating the same, said oscillating member having means for supporting the rear end of the main feed bar, means connected to the oscillating member for moving the feed bar back and forth, and means connected to said oscillating member for moving said sleeve back and forth on said main feed bar.
2. A sewing machine including in combination a standard, a relatively small work supporting cylinder carried thereby and projecting therefrom, a main feed bar located in said cylinder and extending lengthwise thereof into said standard, a main feed dog carried thereby, a sleeve mounted on said main feed bar for endwise movement thereon, an auxiliary feed dog carried by said sleeve, means for raising and lowering the front end of said feed bar together with the sleeve thereon, an oscillating member located in said standard, means for oscillating the same, said oscillating member having means for supporting the rear end of the main feed bar, means connected to the oscillating member for moving the feed bar back and forth, means connected to said oscillating member for moving said sleeve back and forth on said main feed bar, said last-named means including a rock lever pivoted to the main feed bar, a link pivoted to the sleeve and having an adjustable connection with the rock lever, and an arm rigid with the oscillating member and having pivotal connection with the rock lever.
3. A sewing machine including in combination a standard, a relatively small work supporting cylinder carried thereby and projecting therefrom, a main feed bar located in said cylinder and extending lengthwise thereof into said standard, a main feed dog carried thereby, a sleeve mounted on said main feed bar for endwise movement thereon, an auxiliary feed dog carried by said sleeve, means for raising and lowering the front end of said feed bar together with the sleeve thereon, an oscillating member located in said standard, means for oscillating the same, said oscillating member having means for supporting the rear end of the main feed bar, means connected to the oscillating member for moving the feed bar back and forth, means connected to said oscillating member for moving said sleeve back and forth on said main feed bar, said last-named means including a rock lever pivotally carried by said main feed bar and bodily moving therewith, said rock lever having a depending arm provided with a slot, a link connected to a pivot bolt adjustable in said slot and to said sleeve, a rigid arm carried by the oscillating member extending substantially horizontally therefrom, said rock lever having a substantially horizontal arm pivotally connected to said rigid arm on the oscillating member.

In testimony whereof I affix my signature.
JAMES R. MOFFATT.
